UNITED STATES PATENT OFFICE.

JOHN R. MCGIFFERT, OF DULUTH, MINNESOTA, ASSIGNOR TO CLYDE IRON WORKS,
OF DULUTH, MINNESOTA, A CORPORATION OF MAINE.

ENGINE FOR USE IN LOGGING AND THE LIKE.

Application filed April 24, 1923. Serial No. 634,285.

The present improvements have more particular regard to a change speed mechanism designed for use in connection with a skidding engine, i. e., an engine connected to 5 drive winding drums for cables such as are employed in the logging operation known as skidding. In such operation a cableway is usually supported at one end on a suitable portable derrick, with which 10 the skidding engine is associated, and a tree, or other fixed support, and two lines are utilized, one a skidding line for drawing the log in and the other an outhaul line. In 15 mechanism of this type where greatly varying loads require to be handled and where it is also desirable to operate at as high a speed as possible, there is great advantage in providing two speed mechanism for driving the winding drums. Thus in such log 20 skidding operation the winding in of the outhaul line imposes a comparatively light load on the engine and the logs which are drawn in by the winding of the skidding line vary greatly in size. 25 In mechanism of the character described it is usual to connect together or intergear the two drums whereby the two lines in question are operated so that, for example, the outhaul line will pay out at substantially 30 the same speed as the skidding line is drawn in and thus serve to hold the load after it is lifted to the carriage at approximately an even height relative thereto. To accomplish 35 this result it is accordingly necessary that any change of speed should apply simultaneously to both such drums.

The object of the present invention accordingly is to provide a change speed mechanism which may be interposed between an 40 engine and a pair of drums driven thereby, whereby the speed of the latter may be simultaneously changed, a further object being the provision of positive means for insuring disengagement of one chain of gearing to 45 such drums before the other is engaged.

To the accomplishment of the foregoing and related ends, the invention, then, consists of the means hereinafter fully described and particularly pointed out in the claims, 50 the annexed drawings and the following description setting forth in detail certain mechanism embodying the invention, such disclosed means constituting, however, but one of various mechanical forms in which 55 the principle of the invention may be used.

In said annexed drawings:—

Fig. 1 is a broken side elevation of a portable derrick with an engine and pair of winding drums shown as mounted thereon, said engine being connected with said drums 60 by means of my improved change speed mechanism; Fig. 2 is a plan view of such mechanism; Fig. 3 is partly a front elevation and partly a central section of such mechanism shown on a somewhat larger 65 scale; and Fig. 4 is a transverse section of such mechanism taken on a broken plane indicated by the line 4—4, Fig. 3.

The engine 1, as usual where designed for field use as in log skidding, is a steam engine 70 and is mounted alongside a boiler 2 at one end of a platform 3 mounted on suitable trucks or otherwise rendered portable. The drums 4 and 5, on which the skidding line and outhaul line (not shown) are respectively wound, are mounted in a suitable frame 6 immediately in front of such engine and boiler and, as previously indicated, said drums are intergeared, this being accomplished through the medium of a shaft 7 75 supported above and between said drums and carrying pinions 8 and 9 that mesh with gears 10 and 11 on said drums, respectively. The crank shaft 13 of the engine instead of being directly intergeared to drive the adjacent 80 drum 4 is connected therewith through the medium of the power-transmission mechanism 14, which will now be described in detail, having more particular reference to Figs. 3 and 4. 90

Said crank shaft is provided with two pinions 15 and 16, keyed or otherwise fixedly secured thereto and of different diameters so as to be capable of driving shaft 17 of the change speed mechanism at different speeds 95 through the medium of gears 18 and 19 on the latter wherewith said pinions 15 and 16 respectively mesh. A pinion 20 fixedly secured on shaft 17 meshes with gear 10 on drum 4 so that the latter and thus intergeared drum 5 may be driven at correspondingly different speeds. 100

The gears 18 and 19 are loosely mounted on shaft 17 and are respectively provided on their inwardly directed sides with integral clutch members 22 and 23, the friction surfaces of which are adapted to engage with opposed clutch members 24 and 25 that form parts of a friction head 26. The latter being non-rotatably secured to 110

shaft 17 by means of keys 28 and also being held against longitudinal movement relatively to said shaft by means of split collars 29 which are set into said shaft.

5 While various means may be employed for moving either gear 18 or 19 as desired inwardly, so as to bring the corresponding clutch member 22 or 23 into frictional engagement with the opposed clutch part of 10 head 26, I preferably employ the two air thrust mechanisms, one at each end of said shaft 17, such mechanisms being of identical construction and each comprising a cylinder drum 30 within which is reciprocably mounted a piston 31 that acts on a thrust pin 32 extending centrally through the center of shaft 17 to a cross bar 33 that is movable in a slot 34 in said shaft. Each such cross bar engages with a collar 15 20 35 that in the one case bears against the outer face of gear 18 and in the other case against the outer face of gear 19. The air thrust cylinders 30 are shown as fixed on the shaft and so turn with it, the air pipes 36 that are connected with such cylinders being thus connected through the medium of glands 37 which revolve on the pipes so that the latter may remain in fixed position. The air is directed into one cylinder and exhausted from the other alternately, this being simultaneously accomplished by the operation of a suitable valve, as need not be described in detail. It will of course be understood that any suitable means may be provided, in lieu of such air thrust cylinders, for thus forcing one of said gears 18 and 19 inwardly and simultaneously withdrawing the other so as to secure driving connection between the crank shaft 13 and shaft 17 through either pinion 15 and gear 18 or pinion 16 and gear 19.

40 It is of course quite essential that when one of said gears 18 and 19 is thus clutched to shaft 17, the other should first be thrown out of engagement with the latter. To this end I mount on shaft 17 between the inner faces of said gears 18 and 19, respectively, and the adjacent collars 29, a collar 40 and a collar 41 that are slidable along the shaft 45 but are keyed thereto so as to be prevented from turning about said shaft. These two collars are held a fixed distance apart by means of a plurality of thrust bars 42 (shown as three in number in Fig. 4, only one of such bars, however, appearing in Fig. 3). Such bars extend through holes 43 in the friction head 26 and are provided with turnbuckles 44 so that their length may be adjusted as the friction faces on said head and on friction members 22 and 23 50 wear down.

55 As a result of the foregoing construction, if the thrust is removed from gear 18 and applied to gear 19, the first result will be 60 the forcing out of engagement of said gear

18 followed instantly by the engagement of gear 19 and vice versa. In other words, the disengagement of one gear is insured before the other is engaged. It will be seen from the foregoing that my improved 70 change speed mechanism is not only simple and compact but that all of the operating parts are completely housed and thoroughly protected including the friction clutches whereby the gears 18 and 19, respectively, 75 are engaged as desired with shaft 17.

80 Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

85 1. In power transmission mechanism, the combination of a drive shaft, a second shaft parallel therewith, two pairs of intermeshing gears of different ratios, one of each such pair of gears being fixed on said drive shaft and the other being mounted on said second shaft so as to be normally both rotatably and longitudinally movable relatively thereto, a member to be driven mounted on said second shaft between the two gears thereon, and means including a member rigidly interconnecting said gears and adapted to move either one thereof on said second shaft to fixedly engage same with said member and simultaneously to move the other gear positively to disengage the same from said shaft.

90 2. In power transmission mechanism, the combination of a drive shaft, a second shaft parallel therewith, two pairs of intermeshing gears of different ratios, one of each such pair of gears being fixed on said drive shaft and the other being mounted on said second shaft so as to be normally both rotatably and longitudinally movable relatively thereto, a member to be driven mounted on said second shaft between the two gears thereon, complementary friction members carried by said gears, respectively, means connected 95 with each of the latter adapted to force the same inwardly along said shaft, and a rigid thrust member interposed between said gears whereby the one thereof is positively disengaged from said member before the other is brought into engagement therewith.

100 3. In power transmission mechanism, the combination of a drive shaft, a driven shaft parallel therewith, two pairs of intermeshing gears of different ratios, one of each such pair of gears being fixed on said drive shaft and the other being mounted on said driven shaft so as to be normally both rotatably and longitudinally movable relatively thereto, such longitudinal movement, depending on 105

its direction, serving to engage said gears with or disengage the same from said driven shaft, and means including a member rigidly but adjustably interconnecting said gears and adapted to move either one thereof on said driven shaft thus to fixedly engage same thereto and simultaneously to move the other gear positively to disengage the same from said shaft.

10 4. In power transmission mechanism, the combination of a drive shaft, a driven shaft parallel therewith, two pairs of intermeshing gears of different ratios, one of each such pair of gears being fixed on said drive shaft and the other being mounted on said driven shaft so as to be normally both rotatably and longitudinally movable relatively thereto, a friction head fixedly mounted on said driven shaft between the two gears thereon, complementary friction members carried by said gears, respectively, means connected with each of the latter adapted to force the same inwardly along said shaft, and a rigid thrust member interposed between said gears whereby the one thereof is positively disengaged from said head before the other is brought into engagement therewith.

5. In power transmission mechanism, the combination of a drive shaft, a driven shaft parallel therewith, two pairs of intermeshing gears of different ratios, one of each such pair of gears being fixed on said drive shaft and the other being mounted on said driven shaft so as to be normally both rotatably and longitudinally movable relatively thereto, a friction head fixedly mounted on said driven shaft between the two gears thereon, complementary friction members carried by said gears, respectively, means connected with each of the latter adapted to force the same inwardly along said shaft, and a rigid thrust bar of adjustable length interposed between said gears, whereby the one thereof is positively disengaged from said head before the other is brought into engagement therewith.

6. In power transmission mechanism, the combination of a drive shaft, a driven shaft parallel therewith, two pairs of intermesh-

ing gears of different ratios, one of each such pair of gears being fixed on said drive shaft and the other being mounted on said driven shaft so as to be normally both rotatably and longitudinally movable relatively thereto, a friction head fixedly mounted on said driven shaft between the two gears thereon, complementary friction members carried by said gears, respectively, thrust pins extending inwardly from the respective ends of said driven shaft and connected with the corresponding gears to force the same inwardly along said shaft, a collar slidably mounted on said shaft in contact with the inner face of each of said gears, a plurality of thrust bars of adjustable length slidably held in said head in circumferentially spaced relation and connecting said collars, whereby the one of said gears is positively disengaged from said head before the other is brought into engagement therewith.

7. In power transmission mechanism, the combination of a drive shaft, a driven shaft parallel therewith, two pairs of intermeshing gears of different ratios, one of each such pair of gears being fixed on said drive shaft and the other being mounted on said driven shaft so as to be normally both rotatably and longitudinally movable relatively thereto, a friction head fixedly mounted on said driven shaft between the two gears thereon, complementary friction members carried by said gears, respectively, thrust pins extending inwardly from the respective ends of said driven shaft and connected with the corresponding gears to force the same inwardly along said shaft, air-cylinders mounted on the ends of said shaft, pistons in said cylinders acting on the corresponding thrust pins, a collar slidably mounted on said shaft in contact with the inner face of each of said gears, a plurality of thrust bars of adjustable length slidably held in said head in circumferentially spaced relation and connecting said collars, whereby the one thereof is positively disengaged from said head before the other is brought into engagement therewith.

Signed by me, this 19th day of April, 1923.
JOHN R. MCGIFFERT.
